UNITED STATES PATENT OFFICE.

FRANK W. MIX, OF TERRYVILLE, CONNECTICUT, ASSIGNOR TO EAGLE
LOCK COMPANY, OF SAME PLACE.

DESIGN FOR KEY-BOWS.

SPECIFICATION forming part of Design No. 11,615, dated January 20, 1880.

Application filed December 26, 1879. Term of patent 7 years.

To all whom it may concern:

Be it known that I, FRANK W. MIX, of Terryville, in the county of Litchfield and State of Connecticut, have invented a Design for a
5 Key-Bow, of which the following is a specification.

My design is represented by the accompanying drawing of a key.

The bow *a* of the key is formed open, with
10 spindles *c*, that connect the longer side of the bow. The spindles *c* are shown as formed with a knurl at their mid-length and tapering from the center to the opposite ends; but those features may be varied.

15 The bow may be of the rectangular form shown, or oval or other shape, without affect-

ing the general appearance of the design which is given by the spindles, and which is intended to match what is known as the "Queen Anne" style of furniture.

The ornamental appearance may be increased by burnishing and stippling in any desired manner.

I claim as my design and desire to secure by Letters Patent—

The design for key-bows, consisting of the spindles *c*, applied to the open frame of the bow, substantially as shown.

FRANK W. MIX.
